DE LOS A. LAWTON

DOOR FASTENER

Filed Oct. 22, 1923

FIG. 1.

FIG. 3.

FIG. 4.

FIG. 5.

INVENTOR
D. A. Lawton
BY Howard F. Emerson
ATTORNEY

UNITED STATES PATENT OFFICE.

DE LOS A. LAWTON, OF ROME, NEW YORK.

DOOR FASTENER.

Application filed October 22, 1923. Serial No. 669,981.

To all whom it may concern:

Be it known that I, DE LOS A. LAWTON, a citizen of the United States of America, of Rome, in the county of Oneida, in the 5 State of New York, have invented new and useful Improvements in Door Fasteners, of which the following, taken in connection with the accompanying drawings, is a full, clear, and exact description.

This invention relates to a catch or fastener for doors, drawers and other swinging or sliding closures and involves the use of a pair of opposed spring jaws on one of the parts as for example, the door or 15 drawer adapted to frictionally engage opposite sides of a keeper on the other part such as the door casing or fixed part of a cabinet for frictionally holding the closure in its closed position and permitting it to 20 be readily opened at will.

The main object is to provide a catch or fastener of this character in which the keeper and friction lock cooperate to not only frictionally hold the closure in its 25 closed position but also limit the closing movement of the closure and to support said closure against sagging when closed.

Another object is to enable the keeper and lock to be easily and quickly installed 10 and firmly held in operative position without the use of screws or other turning elements.

Other objects and uses relating to specific parts of the device will be brought 15 out in the following description.

In the drawings:-

Figure 1 is a horizontal sectional view of a portion of a cabinet having a door and 10 jam equipped with my improved catch or fastener.

Figures 2 and 3 are enlarged longitudinal and transverse sectional views taken respectively on lines 2-2, and 3-3, Figure 1.

Figure 4 is a perspective view of the 15 main body of the case for receiving the spring lock.

Figure 5 is a perspective view of the cover for the lock case.

In order that my invention may be clearly 20 understood, I have shown a portion of a cabinet case —A— having a door —A'— hinged at —a— along one of its upright edges to swing into an opening in the case

with its free edge adjacent the door jam as —a— of the case —A—.

The free edge of the door is provided with a suitable friction lock adapted to cooperate with a keeper, and the adjacent edge of the door jamb or stile for holding the door in its closed position and also for supporting the door against sagging and limiting its inward swinging movement.

The locking device preferably comprises a cylindrical cup-shape casing —1— having a circular cover plate —2— suitably applied to the open side of the casing to form an intervening chamber for the reception and retention of a pair of opposed spring jaws —3— which preferably form the ends of a circular spring ring —4— as shown more clearly in Figures 2 and 3.

The casing —1— is provided with a base plate —5— and a marginal flange —6— projecting therefrom. The base plate —5— and marginal flange —6— are provided with a radial slot —7— extending inwardly from one side thereof and concentrically around the axis thereof for receiving the keeper presently described.

The locking ring —4— is seated within the casing —1— against the side walls thereof and is preferably divided through one side between the spring jaws —3— to form a passage —8— for the keeper, said passage being registered with the slot —7— when the ring is properly assembled in the case.

The spring jaws extend inwardly at opposite sides of a passage —8— beyond the axis of the casing and are preferably curved in opposite directions to conform to the curvature of the keeper and are spring tensioned toward each other to frictionally grip the periphery of said keeper, the curved inner ends of the jaws being substantially concentric with the axis of the casing.

The marginal edge or flange —6— of the casing —1— is provided with a plurality of, in this instance three, bendable tongues —9— which after the spring ring —4— has been placed in operative position, are bent over and upon the inner face of the ring to hold the latter in place.

The cover plate —2— is provided with a plurality of, in this instance four, slots or notches —10— in uniformly spaced re-

- lation circumferentially for receiving a corresponding number of spurs —11— which project inwardly and axially from the flange —6— of the casing —1—, said plate —2— 5 being also provided with a central aperture —12— and an inward depression —13— for receiving a nail —14— by which the plate —2— is secured to the adjacent edge of the door.
- 10 That is, the free edge of the door is provided with a socket —15— of just sufficient size to easily receive the plate —2— and casing —1— wholly within the outer edge of the door.
- 15 The plate —2— is first placed in the socket —15— flatwise against the inner wall thereof and is secured in place by driving the nail or screw —14— through the opening —12— and into the door until its head 20 is seated firmly against the outer face of the plate wholly within the depression —13—, it being understood that the plate —2— had been properly adjusted to enable the spurs —11— to pass through the slots 25 or recesses —10— when the casing is adjusted for use.
- After the plate —2— has been properly secured in place, the casing —1— with the spring jaws —3— therein is inserted in the socket —15— in the edge of the door with 30 its spurs —11— registering with the slots or notches —10— and is then driven or pressed into place to cause its spurs to pass through the slots —10— and into the wood 35 of the door with its slot —7— extending horizontally and its open side facing inwardly, the spurs being of sufficient length to extend some distance beyond the plate —2— and into the door to firmly hold the 40 case and plate in operative position against relative rotation and also against endwise movement.
- The inner side of the free edge of the door is also provided with a slot —16— registering with the slot —7— and of just sufficient vertical height to receive the keeper or rather, about the same vertical width as the slot —7— as shown more clearly in Figure 3.
- 45 The keeper consists in this instance, of a cylindrical stud —17— having a tapered shank —18— and a stop flange —19— between the stud and tapered shank.
- The keeper is placed in operative position 50 with its stud —17— in the path of movement of the slot —7— of the casing —1—, by driving its tapered shank —18— into the adjacent edge of the door jam or casing —1— as shown in Figure 2 until 55 the flange —19— is firmly impinged against the inner edge of the casing thereby allowing the stud —17— to project into the door opening in registration with the slot —7— when the door is closed.
- 60 When the keeper is properly secured in place and the door is closed, the stud —17— will be substantially coaxial with the curvature of the spring jaws —3— and inner end of the slot —7— and will also extend axially beyond the outer wall or base plate 70 —5— of the casing and also beyond the spring jaws —3— but will terminate a short distance from the outer face of the plate —2— so as to permit said stud to readily enter the slot —7— and passage —8— and 75 between the jaws —3— when the door is closed, under which conditions, the inner end wall of the slot —7— will serve as a stop for limiting the inward swinging movement of the door while the upper and lower 80 walls of the slot will also serve to ride upon the corresponding faces of the studs —17— to guide the door in its closing movement and also to hold the door against vertical movement relatively to the casing. 85
- The inner and outer ends of the jaws —3— are normally spaced a distance apart less than the diameter of the stud —17— and are tensioned toward each other, whereby when the door is closed they will ride 90 upon opposite sides of the periphery of the stud until their concave faces are registered with the adjacent side of the stud —17— whereupon they are automatically 95 spring pressed against the stud to frictionally hold the door in its closed position and still permit the door to be easily opened by the usual "pull" or knob, against the action of the spring jaws when desired.
- If desired, the shank —18— and nail 100 —14— may be provided with spurs or otherwise roughened to more firmly hold them in operative position as shown in Figure 2.
- By making the case —1— and its cover plate —2— circular the socket —15— for receiving them may be easily and quickly bored to the desired size to enable them to fit snugly therein.
- 105 The device is shown as applied to the door of a cabinet but obviously, it may be used as a fastener for drawers and other closures and the structural parts may be varied within certain limits without departing from the spirit of this invention, and therefore, I do not wish to limit myself 110 to the precise construction shown and described.
- I claim:
- 115 A door fastener comprising a circular disc having peripheral notches in circumferentially spaced relation and a circular cup-shaped member of substantially the same diameter as the disk and having its open end provided with spurs entering said notches and adapted to be driven into the door to hold the disk and cup-shaped member in operative position thereon, the outer end wall of the cup-shaped member being 120 provided with a radial slot opening through the periphery thereof, a spring ring seated 125
- 130

against the inner faces of the peripheral walls of the cup-shaped member and having its ends at opposite sides of the slot returned inwardly at opposite sides of the 5 axis of said member to form spring jaws and a keeper having one end adapted to be driven into the door frame and its other end provided with a circular boss project-

ing into the path of movement of the slot in the door to be frictionally engaged by 10 said jaws when the door is closed for holding the door in its closed position.

In witness whereof I have hereunto set my hand this 15th day of October, 1923.

DE LOS A. LAWTON.
